(57) **CLAIM**

The ornamental design for a school bus lunch bag, as shown and described.

DESCRIPTION

FIG. 1 is a perspective view of a school bus lunch bag design showing my new design.

FIG. 2 is a front view of a school bus lunch bag.

FIG. 3 is a rear view of a school bus lunch bag.

FIG. 4 is a left side view of a school bus lunch bag.

FIG. 5 is a right side view of a school bus lunch bag.

FIG. 6 is a top view of a school bus lunch bag; and,

FIG. 7 is a bottom view of a school bus lunch bag.

The broken lines shown in the drawings depict stitching which forms part of the claimed design.
